UNITED STATES PATENT OFFICE

2,481,983

RAILWAY CROSSTIE

Joseph Dell, Windber, Pa.

Application March 31, 1948, Serial No. 18,235

1 Claim. (Cl. 238—288)

1

This invention relates to railway cross-ties and has more particular reference to ties adapted for use in mine railways and which have rail holding means associated therewith.

One object of the invention is to provide a cross-tie of this general type which carries means for joining the abutting ends of two rails together.

Another object of the invention is to provide a cross-tie, as above characterized, in which the rail joining means is in the form of a fishplate mounted adjacent one end of the cross-tie and carrying fish bolts.

Another object of the invention is to provide a cross-tie, as above characterized, in which the fish bolts are rigidly secured to the fishplate and wherein wedging means are employed to hold the fish bolts in engagement with the abutting rails.

A further object of the invention is to provide a cross-tie, as above characterized, which comprises few parts, thereby eliminating bolts, nuts and pins, etc., which are liable to become loose or frozen, and one which is simple in construction, easy to install and remove, and efficient and durable in operation.

A still further and more specific object of the invention is to provide an improved type of rail joining member.

Other objects and advantages of the invention will appear in the following specification when considered in connection with the accompanying drawings, wherein:

Fig. 1 is a perspective view, with parts broken away, of a cross-tie constructed in accordance with the present invention, with track rails shown mounted thereon;

Fig. 2 is a plan view, with parts broken away, of the cross-tie shown in Fig. 1;

Fig. 3 is a front elevational view of the cross-tie shown in Fig. 1;

Fig. 4 is a fragmentary front elevational view, partly in cross section, showing details of the fishplate; and

Fig. 5 is a fragmentary side elevational view showing how the wedge is used with the cross-tie.

It is customary in laying track for mine railways and the like, to employ cross-ties which carry means for clamping the rails to the cross-ties by a wedging operation, thereby eliminating the use of bolts or spikes. One form of such a cross-tie is shown in U. S. Patent No. 917,489, issued on April 6, 1909, to J. J. Ross for cross-tie. However, cross-ties of this type make no provision for securing the abutting ends of two rails

together and the usual types of fishplates and fish bolts are employed for this purpose when such cross-ties are used.

In general, the present invention provides a cross-tie of the wedge-actuated clamping type provided with a fish-plate rigidly secured adjacent one end and in which the fish bolts are held in place by the same wedging action which clamps the rails to the cross-tie.

Referring now to the drawing, there is illustrated in Figs. 1, 2 and 3, a cross-tie constructed in accordance with the present invention and the manner in which it is employed to secure together the abutting ends of a pair of track rails. As there shown, a cross-tie 10 supports and has clamped thereto a right hand rail 11 and a pair of left hand rails 12, 13 having their abutting ends joined and secured together by a connecting member 14 carried by the cross-tie adjacent one end thereof. The rails are of the usual type employed in mines and quarries and comprise a head 15, web 16 and a flanged base 17.

In the particular embodiment illustrated, the cross-tie 10 is substantially identical in construction to that shown in the above mentioned patent to Ross and comprises an elongated body member 18, having its ends bent upward and inward to form hook-like terminals or abutments 19. The body member 18 is preferably made of an inverted U-shaped metal channel member.

Means are provided for holding the rails upon the cross-tie and, as shown, such means may comprise a pair of lugs or clamps 20, each secured on the upper surface of the body member 18 inwardly of one of the upturned ends. In the particular embodiment shown, the clamps 20 are preferably made of U-shaped metal channel members having one end bent upward to provide a clamping surface. The clamp members 20 are rigidly secured to the cross-tie in any suitable manner, and in the particular embodiment illustrated they are riveted to the body member.

After the rails are placed upon the cross-ties, they are forced inwardly, with the inner portions of their flanged bases 17 wedged under the clamp members 20, by driving tapered wedge members 21 between the abutments 19 and the webs 16 of the rails. The wedge members 21 are preferably made of wood and are driven forward to exert a firm lateral pressure upon the rails to contact with the clamping members 20 to rigidly hold the rails in position.

Means are also provided for securely joining the abutting ends of a pair of rails and, as shown, such means, indicated generally at 14,

may comprise a rectangular connecting member or fishplate 22 suitably secured to one of the clamping members 20. In the particular embodiment illustrated, the fishplate is made of metal and is welded to the outer end of the left hand clamping member 20 in substantially parallel relation to the webs of the abutting rails 12, 13 (see Fig. 4).

At least two horizontally spaced projections or fish bolts 23 are rigidly secured to the fishplate. In the particular embodiment shown, the fish bolts 23 are welded to the fish plate and are positioned to be in alignment with and project through corresponding bolt holes 24 formed in each of the abutting end of the rails 12 and 13, when the ends of the rails are forced inwardly by the left hand wedge member 21. There is at least one hole 24 in each of the abutting ends of the rails 12 and 13, and when a fish bolt 23 projects through its corresponding aligned hole 24, the abutting ends of the rails 12 and 13 will be securely held together. Usually, the abutting ends of the rails are not held in actual engagement, but are separated a slight distance to allow for expansion and contraction of the rails, due to temperature changes, in which case, the bolt holes 24 in the webs adjacent the ends of the rails are so located that when they receive the fish bolts 23, the ends of the rails are spaced the proper distance apart.

From the foregoing, it readily will be seen that there has been provided a cross-tie having means for clamping the track rails thereto and having means for securing the abutting ends of two track rails together, all by wedging action, thereby eliminating the use of spikes or bolts and nuts or other loose parts which may be lost, and also facilitates the disassembly and removal of the mine track.

While the invention has been illustrated and described in connection with a Ross cross-tie, obviously, other types of cross-ties could be employed and the connecting member or fishplate can be used with one end of a cross-tie. And, while the clamp 20, the fishplate 22 and fish bolts or projections 23 have been described as made in separate parts and welded together, obviously, the clamp 20 and fishplate 22 could be made from a single piece of steel pressed into proper shape

and the fish bolts could be pressed in the fishplate 22, and, too, the clamp 20, the fishplate 22 and the fish bolts or projections 23 could be formed in one piece and then secured to the member 18.

What is claimed is:

A cross-tie adapted for use at rail joints on a mine railway or the like for clamping the rails and for securing together the abutting ends of a 10 pair of rails comprising an elongated body member having abutments formed on each end, a pair of rail clamps rigidly secured to said body member, each spaced inwardly of one of said abutments in position to engage the inside flange of a 15 rail mounted between the abutments and the clamps, a fishplate rigidly secured to one of said clamps, said plate having a spaced pair of fish bolts rigidly secured thereto and positioned to be received in corresponding aligned openings in the 20 abutting ends of a pair of rails mounted between the clamp carrying the fishplate and its corresponding abutment, said fishplate being spaced from opposing abutment a sufficient distance to permit the jointed rails to be moved laterally to 25 disengage them from the fish bolts, and wedges adapted to be inserted and driven between the rail webs and the abutments for holding the rails in tight engagement with the clamps with the fish bolts received in the openings in the abutting ends 30 of the pair of rails and with the outer ends of the fish bolts pressed against the wedge when the bases of the abutting rails are wedged in their clamped position, whereby the rails will be held securely on the body member and the abutting 35 ends of the pair of rails will be securely held together.
